UNDERGARMENT WAISTLINE MIDRIFF
GIRDLE

Harry Jay Dubner, New York, N. Y.

Application October 20, 1951, Serial No. 252,344

5 Claims. (Cl. 2—43)

1

This invention relates to undergarment accessories, and more particularly is directed to an improved women's diaphragm-midriff flattener and waistline cincher for controlling the abdominal region of the wearer to effect a smooth desirable appearance, and for eliminating any existing bulges when worn to overlie other undergarments such as those at or between hip encircling girdle top and longline brassière bottom, in comfort, streamlining the wearer's form to produce a fashionable foundation for the outer garments.

Among the objects of the invention is to generally improve women's undergarments of the character described which shall comprise few and simple parts that are readily assembled to form a relatively light weight inexpensive construction requiring a minimum of material, which shall serve to control the abdominal region of the wearer as an improved diaphragm-midriff flattener and waistline cincher particularly when worn to overlie a hip encircling girdle top and brassière bottom, which shall comfortably streamline the diaphragm-midriff of the wearer for fashioning a desired smooth foundation for outer garments, which said improved control shall include overlapping elastic bands so constructed and arranged to produce the desired results, which shall eliminate bulges that may exist from wearing other underlying undergarments, which, if desired may be effectively worn selectively as a front or back hooking undergarment to serve as a posture corrective means and as a body brace when required to reduce tired feeling effects, and which shall be practical and efficient to a high degree in use.

Other objects of this invention will in part be obvious and in part hereinafter pointed out.

The invention accordingly consists in the features of construction, combination of elements and arrangement of parts which will be exemplified in the constructions hereinafter described and of which the scope of application will be indicated in the claims following.

In the accompanying drawing in which possible illustrative embodiments of the invention are shown,

Fig. 1 is a perspective view showing an improved diaphragm-midriff flattener undergarment accessory constructed to embody the invention fitted to the trunk or torso of a woman over an underlying hip extending girdle top and brassière bottom in a front hooking position, partly broken away to expose portions of said underlying garments.

Fig. 2 is a plan view of the improved under-

2

garment accessory shown in Fig. 1 constructed to embody the invention spread flat, partly broken away to show details of the construction thereof.

Fig. 3 is a perspective view like Fig. 1, but showing the improved undergarment embodying the invention fitted to a woman's midriff in a back hooking position instead of being front hooking, and

Fig. 4 is a plan view of a modified form of 10 improved undergarment constructed to embody the invention spread flat showing a sectionalized overlapping elastic band structure, fragmentary portions of a brassière and hip extending girdle being shown to indicate the application of the 15 invention for back hooking.

Referring in detail to the drawing, 10 denotes 20 an undergarment accessory constructed to embody the invention shown in Fig. 1, to serve as a woman's diaphragm-midriff flattener and waistline cincher when fitted to trunk or torso T over the midriff abdominal region A of a wearer for embracing the waistline to effect a smooth desirable streamlined appearance and to eliminate 25 any existing bulges thereat, particularly when worn to overlie other undergarment portions, such as a bottom of a longline brassière B and top of a hip extending girdle G as is clear from Figs. 1 and 3.

When said accessory 10 is constructed as front 30 hooking undergarment shown in Figs. 1 and 2, it may comprise a central double elastic band structure 11 formed of an elongated relatively wide stiff elastic band strip 12 and an equally elongated narrower more stretchable elastic band strip 13 secured in position to partially overlie 35 an upper edge border portion 12a of said band strip 12.

Band structure 11 may extend about half the 40 effective waistline length of accessory 10 and made a suitable width to serve as diaphragm-midriff flattener and waistline cincher which for an average size wearer may be five inches wide.

Flanking opposite end edges 11a and 11b of 45 band structure 11 and secured thereto, in any suitable manner, as by stitches 11c and 11d, respectively, there may be provided similar panel members 14 and 15 which may be made of relatively inelastic sheet material.

Said panel members 15 and 14 may terminate 50 along free end edge borders, spaced from said band edges 11a and 11b in a suitable fastener 16 of any conventional construction, such as rows of detachable interconnecting hooks 16a and eyelets 16b, respectively, for selective front or rear hooking as is clear from Figs. 1 and 3. A mul-

multiple row of spaced apart eyelets 16b may be provided to facilitate adjustment for uneven or irregular size requirements.

To provide for counteracting transverse flexing stresses and strains to which the central band structure 11 may be subjected, that is, across the width thereof reinforcing bones or stays 17 may be provided. Said stays 17 may be incorporated into the central band structure 11 in any suitable manner, such as by providing stitched enclosure pocketing tapes 17a secured to the surface thereof with said stays 17 extending in spaced apart down sloping relation toward each other when accessory 10 shown in Fig. 2 is fitted and used as shown in Fig. 1.

Likewise to provide for counteracting undesirable transverse flexing to which panel members 14 and 15 may be subjected reinforcing bones or stays 18 similar to stays 17 may be provided and secured in position to the surfaces of said panel members 14 and 15 by enclosure pocketing tapes 18a, at least one of each of said pocket enclosed stays 18 extending across the mid-portion of said panel members 14 and 15 substantially in parallel relation to said central panel end edges 11a and 11b, respectively, as shown in Figs. 1 and 2.

From the above description and the drawing the utility of the improved diaphragm-midriff flattener and waistline cincher construction is readily understood.

Accessory 10, after being completely manufactured from the parts thereof described above and as shown in Figs. 1 and 2, provides a structural combination which may be comfortably fitted over the bottom edge portion of brassière B and associated upper edge portion of hip encircling girdle G to effect a smooth desirable streamlined appearance about the abdominal region thereby eliminating any bulges of the fleshy midriff particularly just beyond the top border edge of girdle G, the fitting of said accessory 10 as shown in Fig. 1 being secured in position by the front hooking with fasteners 16 in the well understood manner.

By providing band strip 12 of relatively stiffer and wider elastic material than band strip 13 and with the elastic band structure 11 made to extend substantially onehalf the waistline length of the accessory 10 across the back of the wearer so that the portion of elastic strip 12 projecting beyond said overlying edge portion of elastic strip 13 provides a substantially greater stretching resistant force for the front panel members 14 and 15 accessory 10 serves as an effective diaphragm-midriff flattener and also a waist clincher. The portion of elastic strip 13 which projects up beyond the underlying portion of elastic strip 12 at the same time provides a lesser stretching resistance force particularly compatible to smoothing out any fleshy or other bulges thereunder.

The spaced apart transversely extended reinforcing stays 17 and 18 on elastic band structure 11 and on panel members 14 and 15 serve to counteract transversely flexing stresses and strains exerted on accessory 10 on bending or twisting body movements of the wearer.

As seen from Fig. 3, accessory 10 may also be worn as a back hooking undergarment with elastic band structure 11 extending over the front diaphragm-midriff instead of across the back as shown in Fig. 1.

In said last mentioned wearing position of accessory 10, stiffer and wider elastic strip 12 may be located to project above said strip 13 so as to bring the lesser stretching resistance force at or

over the waistline front portion with the panel members 14 and 15, reinforced by stays 18 to serve as a posture corrective means and as a body brace for reducing weak feeling effect due to tiring ambulation.

In Fig. 4 a modified construction of underwear accessory 30 embodying the invention is shown which may be made and used like accessory 10 described above and shown extending over the bottom edge of brassière B and upper edge of girdle G for front or rear hooking in Figs. 1 and 3, respectively, except that double elastic band structure 31 is sectionalized to provide two end disposed parts releasably fastened together by rows of hooks 36a and cooperatively positioned eyelets 36b. Band strips 32 of said sectionalized band 31 may be made like said strip 12 of band structure 11 of relatively stiffer and wider elastic than strips 33 of said band structure 31, each strip 33 being positioned to partially overlie an upper longitudinal edge border 32a of strip 32.

Sectionalized band strips 32 and 33 may be secured by stitches 34a and 34b to opposite ends of a centrally disposed panel member 34 made of relatively inelastic sheet material, suitable transversely extending stays 38 being provided and secured to said panel members 34 and enclosed in pocketing stitched tapes 38a, like that described above for accessory band structure 11.

Also similar transverse flex-counteracting stays 37 may be provided on mid-portions of said sections of band structure 31.

Accessory 30, may if desired, be fitted and worn like accessory 10 as above described and shown in Figs. 1 and 3 and for the same purposes.

It has been found that actual use of undergarment accessories 10 and 30 control the midriff of the wearer comfortably with a reduction of the waistline measurement from two to five inches.

While accessory 10 or 30 has been described above and shown as a women's undergarment accessory, it may also be used by men as an undergarment accessory, that is, as a posture corrective wearing apparel in the same manner described above as for women.

It should be noted that in constructing the improved accessories 10 or 30 a feature of the invention is the ease of manufacture involving simple parts few in number which require no complicated pattern formation assembly thereby lending to low production cost in the range of relatively cheaper undergarment accessories of the character described, and making available to the public such accessories at purchase prices less than any heretofore.

It will thus be seen that there is provided undergarment accessories of the character described whereby the several objects of this invention are achieved and which will be well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention what I claim as new and desire to secure by Letters Patent:

1. A diaphragm flattener and waistline cincher for selective front and rear fastening fit comprising an invertible body encircling band structure of substantially uniform width fitted to extend over the midriff region of the wearer, said

band structure including elastic and inelastic portions, said elastic portion extending approximately one half the effective waistline band length and being formed with a pair of aligned longitudinally extendable strips, one entire longitudinal edge border of each of said strips being arranged in uniformly overlapping relation, and flexure reinforcing stays secured to extend transverse said elastic portion spaced from the ends thereof and interconnecting said strips to counteract flexing stress and strain thereacross, said strips being otherwise free from each other along said overlapping edge border.

2. The diaphragm-midriff flattener and waistline cincher defined in claim 1 in which one of said strips is stiffer to stretching forces and wider than the other of said strips, said elastic portion forming a central panel member and said inelastic portion forming panel members flanking said central panel member to complete a waistline length for the band structure when spread flat.

3. The diaphragm-midriff flattener and waistline cincher defined in claim 1 in which one of said strips is stiffer to stretching forces and wider than the other of said strips, and fastening means extending transversely across said inelastic portion forming panel members flanking said elastic portion when spread flat.

4. The diaphragm-midriff flattener and waistline cincher defined in claim 1 in which one of said strips is stiffer to stretching forces and wider than the other of said strips, and fastening means extending transversely across said elastic portion forming panel members flanking said inelastic portion when spread flat.

5. A four-way diaphragm-midriff flattener and waistline cincher for selective front and rear

fastening fit comprising an invertible body encircling band structure of substantially uniform width fitted to extend over the midriff region of the wearer, said band including elastic and inelastic portions, said elastic portion extending approximately one half the effective waistline band length and being formed with a pair of aligned longitudinally extendable strips, one entire longitudinal edge border of each of said strips being arranged in uniformly overlapping relation, one of said strips being stiffer to stretching forces and wider than the other of said strips, and flexure reinforcing stays secured to extend transverse said elastic portion in angular converging relation to each other and spaced from the ends of said elastic portion for interconnecting said elastic strips to counteract flexing stress and strain thereacross, said strips being otherwise free from each other along said overlapping edge border.
